L. F. MOHNIKE,
WINDMILL CONNECTING BOLT,
APPLICATION FILED OCT. 3, 1917.

1,277,239.

Patented Aug. 27, 1918.

UNITED STATES PATENT OFFICE.

LOUIE F. MOHNKE, OF SHICKLEY, NEBRASKA.

WINDMILL CONNECTING-BOLT.

1,277,239.

Specification of Letters Patent. Patented Aug. 27, 1918.

Application filed October 3, 1917. Serial No. 194,546.

To all whom it may concern:

Be it known that I, LOUIE F. MOHNKE, a citizen of the United States, residing at Shickley, in the county of Fillmore and

5 State of Nebraska, have invented certain new and useful Improvements in Windmill Connecting-Bolts; and I do hereby declare the following to be a full, clear, and exact description of the invention, such as will enable others skilled in the art to which it appertains to make and use the same.

This invention relates to improvements in windmill bolts.

The object of this invention is to improve 15 the construction of windmill bolts so that an ordinary sucker arm of a pump may be detachably secured to the reciprocating rod of the windmill in a quick and reliable manner.

20 Another object of this invention is to provide a bolt capable of securing the rod of an ordinary pump to the lower end of an operating rod of a windmill obviating the necessity of bolts, taps, or the like.

25 A further object of this invention is to provide a sliding bolt and housing therefor whereby it may be secured rigidly to the operating rod of a windmill and is arranged in such a manner as to permit it to readily 30 secure the sucker rod of an ordinary type to the operating rod of a windmill.

A still further object of this invention is to 35 provide a windmill bolt of this character, which will be simple, practicable and comparatively inexpensive in construction and one that can be manufactured and sold at a low cost.

With these and other objects in view the 40 invention consists in the novel combination and arrangement of parts hereinafter more fully described and set forth in the claims.

In the drawings:

Figure 1 is a front elevation of a pump illustrating the sucker rod connection at the 45 lower end of the windmill reciprocating rod, which is partly broken away.

Fig. 2 is a front elevation of the windmill bolt illustrating it applied to the operating rod of a windmill which is in suction.

50 Fig. 3 is a bottom plan view of the bolt.

Fig. 4 is an end elevation.

Fig. 5 is a detail sectional view of said bolt.

Like numerals and references designate

corresponding parts in all the figures of the 55 drawings.

Referring to the drawings, numeral 5 indicates the pump of the type now in general use which consists of a base 6, a casing 7, spout 8, sucker rod 9 and an operating handle 10. The handle 10 is supported to the casing 7 by a suitable bracket 11 having the handle pivotally secured thereto as at 12. One end of the handle is adapted to be pivotally secured to the sucker rod 9 by providing the sucker rod with an opening 13 through which a suitable bolt may extend for forming this connection.

60 My invention relates to means whereby the sucker rod 9 may be detachably secured to the reciprocating operating rod 14 of a windmill. The rod 14 of a windmill is provided at its lower end with an inwardly extending bore or socket 15 for the reception of the upper end of the sucker rod 9. A 65 housing 16 comprises a plate substantially U-shaped in cross section which plate has its flanges or arms of different length and the longer arm disposed uppermost. One end of each arm is bent upwardly to provide 70 an attaching flange 17, this flange being at right angles to the longer arm of the housing. The attaching flange 17 facilitates the detachable securing of the housing to one 75 face of the windmill operating rod 14.

80 The shorter arm or flange of the housing 16 is provided with spaced recesses 18, and is also provided at one end with a slit 18' which facilitates providing of the attaching flange 17.

85 The portion of the shorter arm or flange defined by one recess 18 and the slit 18' is rolled back upon itself to provide a barrel 19 the purpose of which will be hereinafter more fully described.

90 The attaching flange 17 is bent back upon itself to reinforce and strengthen the same and it is provided adjacent each end with a bolt receiving opening which facilitates the detachable securing of the housing to 100 the windmill rod as illustrated in Figs. 1 and 2 of the drawing.

An L-shaped bolt 20 has one portion slidably arranged between the arms or flanges of the plate 16 and the said end is slidable 105 through the barrel 19. The other portion of the bolt is adapted to be moved or swung downwardly until it is located between the

walls of one of the recesses 18 and thereby hold the sliding portion of the bolt which is located between the flanges or arms of the housing 16 in either operative or inoperative 5 position with relation thereto.

A clamping plate 21 is provided adjacent each end with bolt receiving openings which are adapted to receive the bolts 22 thereby rigidly supporting the housing 16 to the 10 reciprocating operating rod 14 of the windmill and at right angles thereto.

The windmill rod 14 and the sucker rod 9 are provided with aligned transverse openings 24 and 24'. The opening 24' is in the 15 sucker rod 9 adjacent the upper end thereof and is adapted to align with the opening 24 when the sucker rod is in the bore 15 of a windmill rod. Thus it can be seen that the sliding portion of the bolt may readily extend 20 through the openings 24 and 24' and thereby detachably secure the sucker rod 9 with the windmill operating rod 14 and obviate the necessity of manually operating the pump.

25 It is to be understood that the sliding portion of the bolt 20 is extended through the openings 24 and 24' of the sucker rod and the windmill rod respectively and the other portion of the bolt 20 is arranged between 30 the walls of the inner recess 18 and thereby held against rearward movement due to the fact that it is at right angles to the arm or flange provided with the recess and it will be seen that the bolt 20 will be 35 held in this operative position and prevent accidental displacement of the detachable connection between the sucker rod and windmill rod.

A cotter key or split key 25 is adapted to 40 extend vertically through each arm of the housing 16 adjacent the outer end thereof and is illustrated in Fig. 5. The key prevents and limits rearward or outward sliding of the bolt when moved to inoperative 45 position and it also prevents the bolt from being entirely withdrawn from the barrel 19 and housing 16.

Copies of this patent may be obtained for five cents each, by addressing the "Commissioner of Patents, Washington, D. C."

When it is desired to operate the pump by the windmill rod 14 it is only necessary to disconnect the end of the handle 10 from the 50 sucker rod 9, force the end of the sucker rod up into the bore 15 of the windmill rod 14 until the opening 24' of the sucker rod aligns with the opening 24 in the operating rod. The bolt 20 is then moved up until it 55 is in the plane or parallel with the arms or flanges of the housing 16 and it is then moved until its sliding portion is through the openings 24 and 24' and then swung downwardly at right angles to the shorter 60 arm and arranged between the inner recess 18 and the sucker rod is connected to the windmill operating rod for operation therewith.

Having thus described my invention what is claimed is:

1. A windmill bolt comprising a housing of substantially U-shaped cross section, attaching plates formed at one end of the housing, means for detachably securing the housing to the operating rod of a windmill, 70 an L-shaped bolt slidably in the housing, means for holding the bolt in an extended position in relation to the housing and means for limiting the movement of the bolt in the opposite direction.

2. A windmill bolt comprising a housing of substantially U-shaped cross section providing long and short flanges, an attaching plate carried by the longer flange of the housing, said shorter flange being provided 80 with recesses, and a barrel, an L-shaped bolt having one portion slidably arranged between the flanges of the housing and the barrel, said bolt adapted to be moved into said recesses in an operative or inoperative 85 position, means for limiting the movement of said bolt in one direction to prevent its entire withdrawal from the housing.

In testimony whereof I affix my signature in presence of two witnesses.

LOUIE F. MOHNIKE.
